CLAIM

The ornamental design for a chair seat, as shown and described.

DESCRIPTION

1.1 is a front perspective view of a chair seat, showing our new design;

1.2 is a side view thereof;

1.3 is a side view thereof, from a side opposite that of 1.2;

1.4 is a front view thereof; and

1.5 is a top view thereof.

The broken lines are shown for the purpose of illustrating the environment of the chair seat and form no part of the claimed design.
